HEATER

Filed July 22, 1929

INVENTOR:
J. W. CUTHBERTSON.
By *Montgomery Smith, Atty*

UNITED STATES PATENT OFFICE

JAMES W. CUTHBERTSON, OF LOS ANGELES, CALIFORNIA, ASSIGNOR TO ARTHUR L. ERICKSON, OF TURLOCK, CALIFORNIA

HEATER

Application filed July 22, 1929. Serial No. 380,192.

My invention relates generally to heating appliances and more particularly to a household heater that utilizes gas as fuel, and the principal objects of my invention are, to generally improve upon and simplify the construction of the existing forms of household gas heaters and to provide a heater that will burn gas, either natural or artificial as fuel, without noxious fumes.

10 Further objects of my invention are, to provide a household gas heater that is relatively simple in construction, inexpensive of manufacture and in which the air that is heated and circulated from the heater is kept entirely separate from the air that is admitted to the burner chamber to support combustion, with the result that only pure heated air is delivered from the heater and the products of combustion and fumes from the burner pass 20 off through a suitably arranged vent.

A further object of my invention is, to provide means whereby practically pure air is admitted to the vent so as to dilute and destroy noxious fumes.

25 With the foregoing and other objects in view, my invention consists in certain novel features of construction and arrangement of parts that will hereinafter be more fully described and claimed and illustrated in the accompanying drawings, in which:

30 Fig. 1 is a vertical section taken through the center of a gas heater constructed in accordance with my invention.

Fig. 2 is a horizontal section taken on the line 2—2 of Fig. 1.

35 Fig. 3 is a vertical section taken through the upper portion of my improved heater and showing the form of heat that is utilized on the heater when the same is locked in a basement or below the building floor.

Referring by numerals to the accompanying drawings which illustrate a practical embodiment of my invention, 10 designates the 40 cylindrical outer shell of the heater, which shell is preferably formed of suitable sheet metal, closed at its lower end by a plate 11 and positioned on top of said shell is a cover plate 12 having a dome shaped central portion 13 that is provided with openings 14.

50 The body of the heater thus constructed is

supported a suitable distance above the floor line by legs 15. Concentrically arranged within the shell 10 is a smaller cylindrical shell 16, the lower end of which terminates a short distance above the bottom plate 15 and the lower end of said shell is closed by a metal plate 17.

55 The space between the plates 11 and 17 constitutes a chamber 18 for a gas burner 19, which latter is connected to a gas supply pipe 20 and formed through the lower portion of the outer shell 10 is a series of openings 21 that permit air to enter the combustion chamber and supply the flames that issue from the burner with oxygen to support combustion.

60 Seated in the plates 11 and 17 and surrounding the burner 19 are the ends of open ended tubes 22 which are for the purpose of admitting air to the chamber within the heating drum 16.

65 Suitably supported within the lower portion of the chamber in the heating drum is a horizontally disposed baffle plate 23 which tends to restrict the free flow of air upwardly through the heating drum and to cause the fresh air entering the lower end of said drum to pass outwardly toward the wall of said drum.

70 An air and gas joint is formed between the upper edge of the shell or heating drum 16 and the top 12 and arranged on the external surface of said shell or heating drum is a shell 24 that is bent to form vertically disposed corrugations and applied to the outer face of this corrugated shell is a layer 75 of thin sheet asbestos.

75 This corrugated shell 24 provides on the external surface of shell 16 a series of relatively small vertically disposed ducts 26 that are open at their lower end and which ducts permit products of combustion and fumes to pass upwardly over the surface of the drum 16 and by means of perforations 27 that are formed through the upper portion of the shell 24, one perforation for each 80 corrugation, these fumes and products of combustion discharge into the upper portion of the circular chamber between the heating drum and outer shell.

85 Leading from the upper portion of the 100

shell 10 is an outlet pipe 28 which communicates with the upper end of a vertically disposed tubular housing 29, both ends of which are closed. Arranged within this tubular 5 housing is a vertically disposed partition 30, the lower end of which terminates a short distance above the bottom of tubular housing 29, thereby providing an opening 31, and leading outwardly from the upper portion 10 of housing 29, directly opposite the outlet tube 28, is an outlet tube 32.

Located within the tubular housing 29, between the partition 30 and the outer portion 15 of the wall of said housing, is an open ended air circulation tube 33, the upper end of which terminates immediately adjacent to the outlet tube 32 and the lower end of which tube 33 extends through the bottom of housing 29 and terminates a short distance 20 below said bottom.

Arranged within the upper portion of the chamber within the heating drum 16 is a ring shaped baffle plate 34, the outer edge 25 of which sits against the wall of the shell or drum 16 and suitably supported above the opening 35 in the center of said baffle ring is a baffle plate 36.

The flames from burner 19 heat the bottom 17 of the heating drum as well as the wall 30 16 of said drum and air from the bottom of the room in which the heater is located, enters the heating drum through tubes 22 and as this air passes upwardly through the drum it is heated and in such condition discharges 35 through the perforated top 13.

In the event that the heater is located in the basement or below the floor the heater is provided with a closed top 13^a from which 40 leads a plurality of heated air ducts 13^b (see Fig. 3).

The flow of air upwardly through the heating drum is to a certain extent restricted and baffled by the plates 23, 34 and 36. Air to support combustion at the burner enters shell 45 10 through openings 21 and the burnt gases and products of combustion pass from beneath the heating drum upwardly through the circular chamber between the heating drum and shell 10 and after passing through 50 outlet pipe 28 the products of combustion pass downwardly through the tubular housing 29 on one side of the partition 30, thence through opening 31 beneath said partition, thence upwardly through the housing on the 55 opposite side of the partition and thence outwardly through outlet opening 32 to the vent.

The corrugated wall 24 that is covered with a sheet of asbestos serves to confine the heat within the heating drum and prevent the 60 radiation of heat therefrom and the greater portion of the fumes resulting from the combustion of gas at the burner passes upwardly in the small ducts between the corrugated wall or shell 24 and the wall 16 of the shell 65 and these fumes discharge through the open-

ings 27 at the upper end of the corrugated wall and pass from thence outwardly through outlet tube 28.

In order to dilute and eliminate in so far as is possible any noxious fumes that may be carried to the vent with the products of combustion, comparatively pure air is permitted to enter the lower end of tube 33 and flow upwardly therethrough and discharge into the upper end of the housing 29 adjacent to the outlet opening therefrom. 75

I have demonstrated in repeated tests and experiments that practically pure air admitted to the products of combustion as they discharge from a gas heater is highly effective in destroying noxious fumes. 80

An especially desirable feature in my improved gas heater is the construction and arrangement whereby the air that is heated and delivered into the room or building in which the heater is located, is kept entirely separate from the air that is delivered to the burner to support combustion and from the products of combustion from said burner. 85

Thus it will be seen that I have provided a gas heater that is relatively simple in construction, inexpensive of manufacture and which may be economically employed for household heating purposes. 90

It will be understood that minor changes in the size, form and construction of the various parts of my improved gas heater may be made and substituted for those herein shown and described without departing from the spirit of my invention, the scope of which is set forth in the appended claims. 95

I claim as my invention:

1. In a gas heater, a housing, a heating drum arranged within said housing, a burner arranged within the housing beneath the heating drum, air inlet pipes leading through the bottom of the housing and through the bottom of said drum, a corrugated wall surrounding the heating drum, a layer of heat insulating material on said corrugated wall, there being openings formed through the upper portion of the corrugated wall and a cover for said shell and heating drum, which cover is perforated above said heating drum. 105

110

2. In a gas heater, a housing, a heating drum arranged within said housing, a burner arranged within the housing beneath the heating drum, air inlet pipes leading through the bottom of the housing and through the bottom of said drum, a corrugated wall surrounding the heating drum, a layer of heat insulating material on said corrugated wall, there being openings formed through the upper portion of the corrugated wall, a cover for said shell and heating drum, which cover is perforated above said heating drum, 115

120

there being openings formed through the upper portion of the corrugated wall, a cover for said shell and heating drum, which cover is perforated above said heating drum and baffle plates located within said drum adjacent to the top and bottom thereof. 125

3. In a gas heater, a housing, a heating drum arranged within said housing, a burner 130

arranged within the housing beneath the heating drum, air inlet pipes leading through the bottom of the housing and through the bottom of said drum, a corrugated wall surrounding the heating drum, a layer of heat insulating material on said corrugated wall, there being openings formed through the upper portion of the corrugated wall, a cover for said shell and heating drum, which cover is perforated above said heating drum, an outlet leading from said shell near its upper end and means for admitting air to said outlet.

4. In a gas heater, a heating drum, a burner arranged beneath said drum, means for admitting air into the lower portion of the chamber within said drum, a corrugated wall surrounding the wall of said drum, a layer of heat insulating material on said corrugated wall and there being outlet openings formed through the upper portion of said corrugated wall and the layer of heat insulating material thereon.

5. In a gas heater, a heating drum, a burner arranged beneath said drum, means for admitting air into the lower portion of the chamber within said drum, a corrugated wall surrounding the wall of said drum, a layer of heat insulating material on said corrugated wall, there being outlet openings formed through the upper portion of said corrugated wall and the layer of heat insulating material thereon and a perforated cover for said heating drum.

35 6. In a gas heater, a heating drum, a burner arranged beneath said drum, means for admitting air into the lower portion of the chamber within said drum, a corrugated wall surrounding the wall of said drum, a layer of heat insulating material on said corrugated wall, there being outlet openings formed through the upper portion of said corrugated wall and the layer of heat insulating material thereon, a perforated cover for said heating drum and baffle plates located within said drum adjacent to its upper and lower ends.

In testimony whereof I affix my signature.
JAMES W. CUTHBERTSON.
